By E. C. Freeman & Co.,
Attn.

UNITED STATES PATENT OFFICE.

GUY ROBERTS, OF WHITEFIELD, NEW HAMPSHIRE.

DESIGN FOR A MILK-BOTTLE PROTECTOR.

53,182.

Specification for Design.

Patented Apr. 8, 1919.

Application filed November 29, 1918. Serial No. 264,738. Term of patent 14 years.

To all whom it may concern:

Be it known that I, GUY ROBERTS, a citizen of the United States of America, residing at Whitefield, in the county of Coos and State of New Hampshire, have invented a certain new, original, and ornamental Design for a Milk-Bottle Protector, of which the following is a specification, reference being had therein to the accompanying drawings.

Figure 1 is a top plan view of a milk bottle protector, showing my new design.

Fig. 2 is a bottom plan view.

Fig. 3 is a front elevation.

Fig. 4 is a rear elevation.

Fig. 5 is a side elevation.

I claim:

The ornamental design for a milk bottle protector, as shown.

In testimony whereof I hereunto affix my signature.

GUY ROBERTS.
